GAS FILLED DISCHARGE TUBE

Gilles Holst, Eindhoven, Netherlands, assignor to
 N. V. Philips' Gloeilampenfabrieken, Eindhoven,
 Netherlands

Application October 17, 1931, Serial No. 569,488
 In the Netherlands October 31, 1930

5 Claims. (Cl. 250—27.5)

This invention relates to a gasfilled discharge tube and more particularly to a rectifying tube having one or more anodes and an incandescent cathode. Besides for rectifiers, the invention is also of importance for other discharge tubes comprising a gasfilling, for example, for luminous tubes known under the name neon tubes.

In such gasfilled discharge tubes the cathode often suffers from collisions of the positive ions 10 of the discharge path which ions are attracted by the cathode. This drawback makes itself particularly manifest when the cathode is an oxide cathode and when a high tension is set up between the anodes and the cathodes. This 15 phenomenon gives rise to disintegration of the cathode and to a shortened life thereof.

According to the invention this drawback is obviated by providing an ion catcher constituted by one or more metal plates, disposed in 20 the vicinity of the incandescent cathode on a side turned away from the anodes and extending parallel or almost parallel to the axis of the cathode.

Due to the speed of the ions in the vicinity of 25 the cathode they tend to fly past the cathode thus colliding with the metal plates where they are neutralized.

The invention is particularly efficacious in the 30 case of discharge tubes in which the cathode is surrounded by a metal sleeve. In this case the ion catcher is so designed that it extends over some distance beyond the open ends of the sleeve. In order to reach the cathode the ions coming 35 from the anode must make a curve, since they must enter through the open ends of the sleeve. Instead of reaching the cathode the largest part of the ions will flash across and strike the ion catcher.

This phenomenon may be furthered by 40 imparting a suitable potential to the ion catcher for which purpose it is provided with a lead wire. A similar result may be obtained by electrically connecting the ion catcher to the incandescent cathode, for example, through a resistance. In 45 this case the ion catcher, due to its large surface, will attract a large number of the ions moving towards the cathode.

The invention will be more clearly understood 50 by reference to the accompanying drawing, representing, by way of example, some forms of construction thereof.

Figure 1 is a perspective side view of a rectifier showing an embodiment of my invention as applied to a multiple anode tube;

55 Fig. 2 is a perspective side view, partly in sec-

tion, of a rectifier tube showing an embodiment of my invention as applied to a single-anode tube.

Referring to Fig. 1, the rectifier tube 1 comprises a cathode 2 and two anodes 3—3. The anodes 3 are supported from one end of the tube from the pinch 12, through which pass the lead wires 13—13 of the anodes 3—3, the lead wires being protected by steatite tubes 14—14 surrounding same. The anodes are separated by a 10 metallic screen 4 carrying a plate 5 acting as an ion catcher, which plate may consist, for instance, of nickel and is provided with a lead wire 7 connected to the plate 4.

The filamentary cathode 2, which is preferably an oxide cathode, is surrounded by a metal sleeve 15 which passes through and is secured to the member 4. The cathode is supported from the pinch 10, and its leads 8 and 9 are protected by tubes 11—11 consisting, for example, of quartz. 20

The ion catcher 5, which is located on that side of the cathode which is turned away from the anodes, may have if desired, an upstanding rim or may be cup-shaped.

My invention is especially well suited for rectifiers adapted for high voltages, in which case the ions in the vicinity of the cathode have a high speed, and their impact on the cathode is highly injurious to the cathode.

Fig. 2 shows a rectifier which has a single 30 anode and in which the discharge path between the anode 3 and the cathode 2 is elongated in a known manner by means of a sleeve 15 surrounding the cathode. The discharge may reach the cathode only through the open ends of this 35 sleeve. In this figure the parts shown also in Fig. 1 are designated by the same numerals.

The sealing-in of the pole wires 8 and 9 is 40 effected in this case by means of two so-called sheath wires for each lead wire which carry together the current. The sleeve 15 and the ion catcher 6 are electrically and mechanically connected together and to the cathode 2 by means of a metal bushing 16 slipped on the lead wire 9 which bushing passes through the ion catcher and the sleeve 15 and is flanged at the upper side. The lead wire 8 passes at 17 freely through apertures provided in the sleeve and ion catcher. A second connection between the sleeve and the ion catcher is established at 18.

In both of the constructions described in order 50 to reach the cathode the ions moving in the discharge path to the cathode must change their direction at the open ends of the sleeve 15. Since the ion catcher 6 is located below the sleeve 55

15, and has a suitable potential, for instance, the cathode potential, the ions will rather flash through to this ion catcher and not reach the incandescent cathode at all.

5 At the bottom side of the discharge tube of Fig. 2 is furthermore located a plate 19 consisting, for instance, of mica and separating that part of the discharge tube which surrounds the stem 20 from the remaining parts of the discharge tube. At this place a space is formed into which the heat rays of the middle portion of the discharge tube penetrate with difficulty. The obturation of such a space may be of importance when the discharge tube contains the vapour of 10 a material of which also a quantity in a solid or liquid state is present in the tube, for instance, in the form of a drop of mercury. The pressure within the tube depends on the temperature at the coolest part of the tube. Consequently the 15 space surrounding the stem 20 which is less warm than the remaining part of the tube may serve for producing a definite pressure in the discharge tube.

20 While the drawing represents rectifiers of a definite type, various modifications are possible without departing from the principle of the invention.

25 The electrodes, for instance, may be of different construction than those shown and not only a plurality of anodes, but more than one incandescent cathode may be used.

30 Furthermore the invention, as stated in the preamble, may also be used in various other gas-filled tubes besides the rectifying tubes described.

35 What I claim is:

1. A rectifier tube having an envelope, a gaseous filling, an incandescent cathode and an anode, the axis of said cathode being perpendicular to the discharge path between the cathode and 40 the anode, a metallic member surrounding said cathode and intercepting the discharge path, and a second metallic member disposed in the vicinity of the cathode on its side turned away from

the anode, the two members being electrically connected with each other.

2. A rectifier tube having an envelope, a gaseous filling, an incandescent oxide cathode and an anode, an open-ended sleeve surrounding said cathode, and a metallic member disposed on the side of the cathode turned away from the anode and in close proximity to said sleeve, said metal member extending beyond the two ends of said sleeve.

3. A rectifier tube for high voltages comprising an envelope, a gaseous filling, an incandescent oxide cathode and an anode, said anode and cathode forming a discharge path between said anode and cathode, which is perpendicular to the axis of said cathode, a sleeve concentrically surrounding the cathode and intercepting the discharge path, said sleeve being open at the two ends, and a metal plate having a plane substantially parallel to the axis of the cathode and being disposed in the proximity of said sleeve on that side of the cathode which is turned away from the anode.

4. An electric discharge tube having an envelope, a gaseous filling, an anode and an incandescent cathode, a conductive member disposed between the anode and cathode and intercepting the discharge path between said anode and cathode, said member substantially surrounding the cathode, and a second conductive member disposed in the vicinity of the cathode on its side turned away from the anode and electrically connected with said cathode.

5. An electric discharge tube having an envelope, a gaseous filling, an incandescent cathode and a plurality of anodes, said anodes being disposed on one side of said cathode, a metallic sleeve surrounding the cathode and intercepting the discharge paths between the cathode and anodes, and a second metallic member in the vicinity of the cathode and on its side turned away from the anode.

GILLES HOLST.
